UNITED STATES PATENT OFFICE.

JOHN THRAILKILL, OF DEXTER, IOWA.

RAIL-JOINT.

SPECIFICATION forming part of Letters Patent No. 699,903, dated May 13, 1902.

Application filed March 3, 1902, Serial No. 96,502. (No model.)

To all whom it may concern:

Be it known that I, JOHN THRAILKILL, a citizen of the United States, residing at Dexter, in the county of Dallas and State of Iowa, 5 have invented certain new and useful Improvements in Rail-Joints; and I do hereby declare the following to be a full, clear, and exact description of the invention, such as will enable others skilled in the art to which 10 it appertains to make and use the same.

This invention aims to provide a rail-joint of novel formation which will present a continuous up-bearing surface at the juncture formed between the ends of adjacent rails, 15 the joint being braced against both vertical and lateral stress.

For a full description of the invention and the merits thereof, and also to acquire a knowledge of the details of construction of 20 the means for effecting the result, reference is to be had to the following description and drawings hereto attached.

While the essential and characteristic features of the invention are susceptible of modification, still the preferred embodiment of 25 the invention is illustrated in the accompanying drawings, in which—

Figure 1 is a perspective view of a rail-joint embodying the invention. Fig. 2 is a trans- 30 verse section. Fig. 3 is a perspective view of one member of the joint. Fig. 4 is a perspective view of the other member of the joint. Fig. 5 is an end view of both members of the joint.

35 Corresponding and like parts are referred to in the following description and indicated in all the views of the drawings by the same reference characters.

The joint comprises the members 1 and 2, 40 which represent the ends of adjacent railroad-rails. The member 1 has spaced extensions 3 in line with side portions of the foot or base and a mortise 4, extended inward for a short distance from the extremity, said mortise 45 opening upward through the tread of the member and having its side walls slightly upwardly flared. The foot of the member and each side of the web are cut away for a short distance from the extremity to form a space 50 to receive the offset portion 5 of the splice-plate 6, which is bolted against the side of the joint and firmly attached to a tie.

The member 2 has a longitudinal extension 7 to snugly fit the mortise 4, the sides of said extension being slightly upwardly diverged 55 to conform to the flare of the sides of the mortise 4. The foot is cut away at each side of the web, as shown at 8, to receive the extensions 3, which embrace opposite sides of the web and in conjunction with the extension 7 60 prevent lateral movement of the members comprising the joint. The extension 7, fitting the mortise 4, prevents any vertical play of the members and insures the formation of a continuous surface for supporting the walls 65 when passing over the joint, thereby preventing any jar or shock, such as commonly experienced in railways having the adjacent ends of rails abutting simply without any interlocking.

When the members are fitted together, a space is provided at each side of the web and extends equally to the right and to the left of the joint and receives the part 5 of the splice-plate, thereby resulting in the forma- 75 tion of a neat and substantial joint. The splice-plates 6 are bolted against opposite sides of the joint, and their horizontal wings are spiked or otherwise firmly attached to a tie. By having the offset portion 5 of each 80 splice-plate overlap the foot of the rail opposite the joint the latter is braced vertically in conjunction with the extension 6, as will be readily comprehended.

Having thus described the invention, what 85 is claimed as new is—

1. In a rail-joint, a member having spaced basal extensions and a longitudinal mortise extended inward from the extremity of the rail and opening upward through the tread- 90 surface, and the other member having the foot of the rail cut away at each side of the web to receive the aforesaid extensions, which embrace the sides of the web, and a longitudinal extension to fit within the said mortise, 95 substantially as set forth.

2. In a rail-joint, a member having spaced longitudinal extensions, and a mortise ex- 100 tended inward from the extremity and having its side walls upwardly flared, and the mating member having the foot cut away at each side of the web to receive the aforesaid spaced ex- tensions and having a longitudinal extension with its sides upwardly diverged to snugly fit

the aforesaid mortise, substantially as set forth.

3. In a rail-joint, a member having spaced longitudinal extensions and a mortise, the 5 mating member having a portion of the foot cut away upon each side of the web to receive the aforesaid spaced extensions and having a longitudinal extension to snugly fit said mortise, and splice-plates secured to opposite 10 sides of the joint and having offstanding

wings to be attached to a tie, each of the splice-plates having an offset portion to fit a cut-away part of the foot of the rail member forming the joint, substantially as set forth.

In testimony whereof I affix my signature 15 in presence of two witnesses.

JOHN THRAILKILL. [L. S.]
